Patented July 21, 1964

198,733

PORTABLE CHARCOAL STARTER

Anthony G. Arena, 9807 Cottage Grove Ave.,
Chicago, Ill.

Filed Nov. 19, 1963, Ser. No. 77,494

Term of patent 14 years

(Cl. D81—10)

FIGURE 1 is a perspective view of a portable charcoal starter, showing my new design, the cover being in open position;

I claim:

The ornamental design for a portable charcoal starter, substantially as shown.
